US0D1083880S

(12) **United States Design Patent** (10) **Patent No.:** **US D1,083,880 S**
(45) **Date of Patent:** **** Jul. 15, 2025**

(54) **FACE CUSHION PAD**

(71) Applicant: **Beijing Zitiao Network Technology Co., Ltd.**, Beijing (CN)

(72) Inventors: **Jinbo Huang**, Beijing (CN); **Jiabin He**, Beijing (CN)

(73) Assignee: **Beijing Zitiao Network Technology Co., Ltd.**, Beijing (CN)

(**) Term: **15 Years**

(21) Appl. No.: **29/886,201**

(22) Filed: **Mar. 6, 2023**

(30) **Foreign Application Priority Data**

Sep. 7, 2022 (CN) 202230591896.0

(51) **LOC (15) Cl.** **14-01**

(52) **U.S. Cl.**

USPC **D14/217**

(58) **Field of Classification Search**

USPC D14/125, 126, 217, 372, 432; D16/300, D16/303, 306, 309, 311–313; D24/110.2, D24/110.3, 120, 157; D29/105–107

(57) **CLAIM**

The ornamental design for a face cushion pad, as shown and described.

DESCRIPTION

FIG. 1 is a front perspective view of a face cushion pad showing our new design;

FIG. 2 is a rear perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof; and,

FIG. 8 is a right side view thereof.

1 Claim, 5 Drawing Sheets
